UNITED STATES PATENT OFFICE.

WILLIAM C. NORTON, OF SALEM, MASSACHUSETTS.

THERMAL GAS-VALVE.

SPECIFICATION forming part of Letters Patent No. 717,904, dated January 6, 1903.

Application filed April 15, 1902. Serial No. 103,013. (No model.)

To all whom it may concern:

Be it known that I, WILLIAM C. NORTON, of Salem, county of Essex, and State of Massachusetts, have invented an Improvement in Thermal Gas-Valves, of which the following description, in connection with the accompanying drawings, is a specification, like characters on the drawings representing like parts.

It is a well-known fact that serious explosions are often occasioned while a building is burning, resulting from the breaking of the gas pipes or fixtures by falling timbers and other causes, permitting the gas to escape into the rooms of the building and to form an explosive mixture with the air, the escaping gas also adding fuel to the flames, and thereby hindering the firemen in their efforts to extinguish them.

The object of my invention is to provide the gas-pipes of a building with a device which will automatically shut off the gas-supply in case of fire. I accomplish this object by providing the gas-pipes at various places throughout a building with automatic valves which act to close the gas-pipes when they are heated to a certain temperature.

I preferably provide the ordinary shut-off valve at the gas-meter with means whereby it may be automatically closed when heated, and yet the valve may be opened and closed without disturbing said automatic means. The particular means of accomplishing the object of my invention which I employ consists, essentially, of a valve which is secured by a readily-fusible solder to the valve-casing, said valve being adapted to drop or be forced across the gas-passage, so as to totally close the same, when the casing is sufficiently heated to loosen the solder.

For a more definite understanding of my invention reference is now made to the accompanying drawings, in which—

Figure 1 is a side elevation of a shut-off valve which is provided with my invention. Fig. 2 is a central cross-section thereof, showing the parts in their normal position. Fig. 3 is a similar section showing the automatic valve in the position which it assumes in the case of fire.

As shown in the drawings, the casing 1 is provided with a turning valve-plug 2, which is preferably tapered and fitted in the casing.

The valve-plug 2 is provided with the usual ports 2^a 2^b and is made hollow, so as to form an inverted frusto-conical shaped or tapering chamber 3, the smaller end of which is adjacent said ports. The upper end of said chamber is closed by a cap 4, which is threaded into the upper end of the valve-plug 2, said cap being locked in position by a screw 5, so that said cap will not be unscrewed when the valve-plug is turned by the application of a wrench to the cap. The ports 2^a 2^b both lead into the lower end of chamber 3, and the surface about each port within the chamber is made smooth to form seats for a solid frusto-conical-shaped supplemental valve-plug 6, which is adapted to engage both of said seats simultaneously and completely close said ports, said supplemental valve-plug perfectly fitting the lower end of the tapering chamber 3. Said supplemental valve-plug is normally suspended in the upper end of said chamber above the ports 2^a 2^b by means of a stem 7, which is threaded at one end into the supplemental valve-plug, its opposite end being connected to the cap 4 by means of a readily-fusible solder 8. The inner side of the cap 4 is preferably slightly recessed, so that said stem may be more readily and securely soldered to the cap. A spring 9 is preferably interposed between the upper end of the supplemental valve-plug 6 and the cap 4, as shown. In placing the parts in position the stem 7 is first soldered to the cap 4, and then the spring is placed on the stem and compressed, and then the threaded end of the stem is screwed into the supplemental valve-plug 6, after which the cap 4 is screwed into the valve-plug 2.

The operation of the above-described device is as follows: In case of fire the valve-casing will be heated and the solder 8 will be melted, disconnecting the stem 7 from cap 4 and permitting the supplemental valve-plug to drop into the position shown in Fig. 3, thus completely closing both ports 2^a 2^b in the valve-plug 2, so that further passage of the gas through the gas-pipe in which the valve is located will be effectually prevented. The weight of the supplemental valve-plug 6 is ordinarily sufficient to cause the same to seat firmly; but I prefer to employ the spring 9, so that the supplemental valve-plug 6 will be more quickly released from the cap 4 when

the solder is melted. Said spring also acts to give the supplemental valve-plug 6 a certain impetus which will drive it more forcibly against its seat. In case also the valve-casing should not be placed in a perpendicular position said spring would still act to force the supplemental valve-plug 6 to its seat when released. When the parts are in the position shown in Fig. 2, the valve-plug 2 may be turned 10 to shut off or turn on the gas in the ordinary way.

It is my intention to provide valves of the form shown in Fig. 2 at each gas-meter throughout a building.

15 While I have herein shown the form of my invention which I consider the most desirable, yet obviously other forms thereof may be constructed without departing from the spirit and scope of my invention.

20 Having thus described my invention, what I claim as new, and desire to secure by Letters Patent, is—

25 1. A valve comprising a casing having a passage therethrough and a valve-chamber which extends to one side thereof, a valve-seat about said passage, a valve-plug arranged in said chamber having a passage therethrough, a supplemental valve-chamber in said valve-plug, a valve-seat about said passage through 30 the valve-plug, a supplemental valve-plug in said supplemental valve-chamber, a fusible support for normally holding said supplemental valve-plug away from its seat, and means for guiding said supplemental valve- 35 plug to its seat when said support is fused, substantially as described.

2. A valve comprising a casing having a passage therethrough, and a chamber which extends to one side of said passage, a valve-seat 40 about said passage, a valve-plug in said chamber, having a passage therethrough, a supplemental valve-chamber in said valve-plug, a valve-seat about said passage through the valve-plug, a supplemental valve-plug in said 45 supplemental valve-chamber, a fusible connection between said supplemental valve-plug

and the inner side of said supplemental chamber which normally holds said supplemental valve-plug out of engagement with its seat, and means for guiding said supplemental 50 valve-plug to its seat when said connection is broken, substantially as described.

3. A valve comprising a casing having a passage therethrough, a valve-plug for closing said passage, having a passage through it, a supplemental valve-chamber in said valve-plug, a supplemental valve-plug in said supplemental valve-chamber, and a fusible support normally holding said supplemental valve-plug removed from its seat, substantially 60 as described.

4. A valve comprising a casing having a passage therethrough, and an inverted conical-shaped chamber into the lower end of which said passage leads, a hollow conical-shaped 65 valve-plug contained in said chamber having a passage through it, a supplemental valve-plug contained in said hollow valve-plug, and a fusible connection between the supplemental valve-plug and the upper end wall of 70 said hollow valve-plug, substantially as described.

5. A valve comprising a casing, a turning plug adapted to close the passage-way through said casing, said valve-plug being made hollow so as to provide a chamber which extends longitudinally thereof and is connected with the valve-port therethrough, a cap closing the upper end of said chamber, a supplemental valve-plug adapted to close the port of said 75 plug, a fusible connection between said cap and said supplemental valve-plug which normally supports said supplemental valve-plug remote from its seat, substantially as described.

80 In testimony whereof I have signed my name to this specification in the presence of two subscribing witnesses.

WILLIAM C. NORTON.
